UNITED STATES PATENT OFFICE

160,267

SOCKET WRENCH

Cecil Dewight McCammon and Luther Lemoine
Mikeworth, Robinson, Ill., assignors to Ohio Oil
Company, Robinson, Ill.

Application September 10, 1949, Serial No. 4,938

Term of patent 14 years

(Cl. D54—16)

To all whom it may concern:

Be it known that we, Cecil Dewight McCammon, a citizen of the United States, residing at Robinson, county of Crawford, and State of Illinois, and Luther Lemoine Mikeworth, a citizen of the United States, residing at Robinson, county of Crawford, and State of Illinois, have invented a new, original, and ornamental Design for a Socket Wrench, of which the following is a specification, reference being had to the accompanying drawing, forming a part hereof.

Fig. 1 is a perspective view of a socket wrench showing our new design;

Fig. 2 is a plan view;

Fig. 3 is a front end view;

Fig. 4 is a rear end view; and
Fig. 5 is a sectional view on the line 5—5 of
Fig. 2.

We claim:

The ornamental design for a socket wrench, as shown.

CECIL DEWIGHT McCAMMON.
LUTHER LEMOIN MIKEWORTH.
